DESIGN FOR A COMBINED FACE PANEL AND BEZEL FOR ASH RECEIVERS

John Visser, Grand Rapids, Mich., assignor, by
mesne assignments, to F. L. Jacobs Company,
Detroit, Mich., a corporation of Michigan

Application March 25, 1936, Serial No. 61,783

Term of patent 14 years

To all whom it may concern:

Be it known that I, John Visser, a citizen of the United States, residing at Grand Rapids, in the county of Kent and State of Michigan, have invented a new, original, and ornamental Design for a Combined Face Panel and Bezel for Ash Receivers, of which the following is a specification, reference being had to the accompanying drawing, forming part thereof.

Figure 1 is a front view of a combined face panel and bezel for ash receivers, showing my new design.

Figure 2 is a side view of the same.

This application is a continuation in part of my application Serial No. D-58,687, filed September 25, 1935.

I claim:

The ornamental design for a combined face panel and bezel for ash receivers, as shown.

In testimony whereof, I affix my signature.

JOHN VISSER.
